UNITED STATES PATENT OFFICE.

ANTHONY J. SOTO, OF SAN BRUNO, CALIFORNIA.

BOTTLE OR JAR COVER.

Application filed April 2, 1921. Serial No. 457,919.

To all whom it may concern:

Be it known that I, ANTHONY J. Soto, a citizen of the United States, residing at San Bruno, in the county of San Mateo and State 5 of California, have invented new and useful Improvements in Bottle or Jar Covers, of which the following is a specification.

This invention relates to closure means for bottles, fruit jars and like articles and has 10 for its object to provide spring actuated clamping mechanism adapted to securely hold in position a cover of an article of the above mentioned character.

Another object of this invention is to provide 15 clamping means adapted to be detachably positioned about the neck of said article for the purpose of supporting its cover through the medium of connecting means adapted to be attached to said clamping 20 means.

Another object of this invention is to provide 25 a device of the character described which is comparatively simple in construction, economical in manufacture, positive in operation, strong and durable.

Other objects and advantages will be apparent during the course of the following description.

In the accompanying drawings forming a 30 part of this specification, and in which like numerals are employed to designate like parts throughout the same.

Fig. 1 is a sectional view of my invention,

Fig. 2 is a front elevation of the same, 35 showing the cover fastening applied to a bottle,

Fig. 3 is a horizontal sectional view taken on the line 3—3 of Fig. 1,

Fig. 4 is a side elevation of the device 40 showing the cover positioned on one side of the bottle, and

Fig. 5 is a horizontal sectional view taken on the line 5—5 of Fig. 1.

In the drawing wherein for the purpose 45 of illustration is shown a preferred embodiment of my invention, the numeral 6 designates a bottle adapted to have its neck encircled by a band, which band includes circular arms 8 and 9, pivoted at 10, and respectively terminating in an apertured extension 11 and a bifurcated extension 12. Pivoted to the extension 11 is a connecting bolt 13 which is adapted to be received within 50 the bifurcated extension 12 and secured therein against displacement by a winged nut 14 adapted to encircle the bolt 13.

In order to be able to swing the irregular shaped cover 15, to one side and thus expose the mouth of the bottle to the atmosphere, a yoke element is pivotally connected to the 60 arm bands through the medium of studs 16, adapted to pierce the band through the inner side thereof and be received in swiveled bars 17, which encircle the lower extremities of the yoke element. This element consists of a 65 pair of spring arms 18 and 19 having their upper extremities receivable within an internally threaded collar 20.

Adapted for vertical movement within the 70 collar 20, is an externally threaded sleeve 21, provided with a knurled top 22. As shown to advantage in Figs. 1 and 2 a spindle 23 penetrates the sleeve 21 and is suitably connected adjacent its lower extremity to the 75 raised portion 24 of the cover 15.

Positioned beneath the sleeve 21 and encircling the spindle 23 is a cap 24 which serves to house one end of a spiral spring 25, which spring has its opposite end encircling the raised portion 24 of the cover 80 15. By referring to Figs. 1 and 3 of the drawing it will be apparent that upon the swinging of the yoke to one side in order to uncover the bottle, the spring 25 will be compressed and partly housed in the cap 24. 85 The cover 15 in addition to the raised portion 24 comprises an outer annular portion grooved at 26 and an inner annular grooved portion 27 terminating in flanges 28. In the outer annular portion I have provided an 90 annular gasket or washer 28 which rests upon the top of the bottle and serves to make the same air tight. For the purpose of retaining the spring arms 18 and 19 in a fixed position, I have riveted to the top of 95 the cover bifurcated fingers 31 and 32 adapted to receive therein the spring arms 18 and 19.

From the foregoing description it is apparent that I have provided a cover fastening which can readily be disposed on the top 100 of a bottle or like article to render the same air tight, and it will be further evident that I have provided means for retaining the cover on the neck of the bottle whereby the 105 cover will be in position for a quick adjustment over the top of the bottle when this operation is desired.

It is to be understood that the form of 110 my invention herewith shown and described, is to be taken as preferred example of the same, and that various changes in the shape,

size and arrangement of parts may be resorted to without departing from the spirit of the invention or the scope of the subjoined claim.

5 Having thus described my invention, I claim:—

In a device of the character described, the combination of a bottle having a beaded neck, a band adapted to extend around the 10 neck of said bottle, said band comprising two semi-circular portions hinged one to the other, means for detachably securing the free ends of said semi-circular band portion, pivoted bars secured to said bands at points 15 diametrically opposite, a substantially **U** shaped yoke having its extremities secured

in said pivoted bars, a collar secured in said yoke, said collar being integrally threaded, a cover having annular rings formed therein, fingers secured on said cover and adapted to contact said yoke, a gasket mounted to one of said annular rings, a stem secured to said cover, a screw threaded sleeve adapted to be threaded in the said collar, means for rotating said sleeve, a cap surrounding said 25 stem and abutting said sleeve, a spring mounted between said cap and said cover for the purpose of holding said cover in contact with said bottle.

In testimony whereof I affix my signature. 30

ANTHONY J. SOTO.
